IGNACIO NAVARRO M., OF CARACAS, VENEZUELA.

DENTAL-CROWN-MAKING MACHINE.

1,346,719.

Specification of Letters Patent. Patented July 13, 1920.

Application filed December 4, 1917. Serial No. 205,380.

To all whom it may concern:

Be it known that I, IGNACIO NAVARRO M., a citizen of Venezuela, and a resident of Caracas, Venezuela, have invented a new and Improved Dental-Crown-Making Machine, of which the following is a full, clear, and exact description.

Among the principal objects which the present invention has in view are: to facilitate the manufacture of dental crowns; to reduce the time expended in the operation; to provide a power machine having substitute parts to permit employment of a machine for various operations; and to provide a machine for performing the entire operation resulting in completing the crown.

Drawings.

Figure 1 is a side view of a machine of the character mentioned constructed and arranged in accordance with the present invention, the machine being disposed for the manufacture of sheet metal blanks from which crown cups are constructed;

Fig. 2 is an end elevation of the same;

Fig. 3 is a side elevation of a portion of the machine showing the elements as arranged for the conversion of the blanks above mentioned into crown cups from which the crowns are constructed, the machine being shown in open position to receive said blanks;

Fig. 4 is a side elevation of the same, showing the machine in closed position, the dotted lines in this figure showing the raised position of the head of the machine and parts connected therewith when employed as a press head;

Fig. 5 is a side elevation of the machine showing the press head as equipped with a die for forming the denture of the crown;

Fig. 6 is a detail view on an enlarged scale showing the disk-cutting dies and section of the press head, the section being taken as on the line 6—6 in Fig. 1;

Fig. 7 is a vertical section of the parts shown in Fig. 6, the section being taken as on the line 7—7 in said Fig. 6;

Fig. 8 is a cross section of the disk-cutting dies, the section being taken as on the line 8—8 in Fig. 7, and showing in conjunction with the dies, a plate arranged to be cut;

Fig. 9 is a detail view on an enlarged scale showing the machine arranged for the manufacture of crown cups, the base of the

machine being in section, the section being taken as on the line 9—9 in Fig. 3;

Fig. 10 is a vertical cross section of the elements arranged as in Fig. 3, the section 60 being taken as on the line 10—10 in Fig. 3;

Fig. 11 is a similar view showing the crown-cup making parts in closed position, and the cup in position for delivery.

Fig. 12 is a top plan view of the female 65 die block for making the completed crown, the machine standards being shown in section, the section being taken as on the line 12—12 in Fig. 5;

Fig. 13 is a face view of one of the sections forming the die block, the view being taken as on the line 13—13 in Fig. 12, the clamping screws in said Fig. 12 being shown in section;

Fig. 14 is a detail view on an enlarged 75 scale and in vertical section showing the die block as loaded with a crown cup, and the die plate with the dies in working position thereto, the section being taken as on the line 14—14 in Fig. 5;

Fig. 15 shows the die members closed;

Fig. 16 is a cross section of the die block, the section being taken as on the line 16—16 in Fig. 12;

Fig. 17 is a cross section of the die members and male-die-holding plate, the section being taken as on the line 17—17 in Fig. 12;

Fig. 18 is a top view of a filling plate used to protect the crown cup-forming plungers;

Fig. 19 is a top plan view of a supporting plate for the male dies;

Fig. 20 is a side view of one of the disks from which the crown is made;

Fig. 21 shows the succeeding step wherein 95 the disk is converted into a crown cup;

Fig. 22 shows a succeeding step wherein the crown cup is converted into a denture crown;

Fig. 23 is a vertical section through the 100 perfected crown.

Description.

The machine shown in the drawings provides among other things for the manufacture of a quantity of crowns such as shown in Fig. 22, simultaneously. The steps following in the operation of the machine result in three distinct products: (1) The disks, one of which is shown in Fig. 20 of 105 the drawings, cut from sheets of metal of approved character; (2) crown cups or fer-

- rules, as shown best in Fig. 21 of the drawings, in which the ends of the crowns are domed or flat as the case may be, and (3) the perfected crowns, one of which is shown 5 in Fig. 22. These crowns are of various characters to correspond with the various molds and dies shown in the drawings and more particularly in Figs. 12 to 15 inclusive thereof.
- 10 In Figs. 1 and 2 of the drawings, the machine is shown as arranged for making the various disks from which the crowns are subsequently shaped.
- The die head 31 as shown best in Figs. 6 15 and 7, is provided with a series of passages 32, the upper edges whereof are sharpened to operate in conjunction with punches 33 mounted in an assembling plate 34 which is supported upon and lifted above a guide 20 plate 35 by means of springs 36. As shown best in Fig. 7, the punches 33 are graduated in length to extend beyond the plate 35 and into the passages 32 successively, thereby cutting the interposed metal sheet to form 25 the disks 37 serially. This avoids the imposition of the maximum strain on the machine and on the feed screw and cross head 39 thereof. The assembling plate 34, the guide 30 plate 35, and die head 31 are structurally united. The plate 35 and head 31 are fixedly spaced apart, being rigidly held by bolts 40 on spacing washers 41, which provided a slit between the plate 35 and the head 31 for the introduction of continuous metal strips 42.
- 35 The strips 42 are held in position to be cut by gage members 43, as shown best in Figs. 6 and 8.
- The disk-cutting mechanism above described is installed in service to be operated 40 upon by the power mechanism and removed therefrom when not employed in cutting the disks. To this end, the plate 35 and head 31 has an end-opening recess 44 at one end of said plate and head, and a side-opening recess 45 at the opposite end thereof. The said recesses in service hold standards 46 and rest on the bosses 47 extended from the base plate 48. The upper ends of the standards 46 are connected by the cross head 39.
- 50 When the disk-cutting mechanism is placed in service, the strips 42 are fed between the plate 35 and the head 31 above the passages 32 in the path of the punches 33. The attendant then engages the hand wheel 55 49 and rotates the screw 50 to lower the end of the same for forcing the shoe plate 51 upon the assembling plate 34, to the end that the assembling plate 34 and punches 33 connected therewith are forced downward, the 55 said punches passing successively through the metal strip 42, which then drops through the passages 32 upon the bed plate 48.
- As indicated by the passages 32, as shown 60 in Fig. 7 of the drawings, and by the tops 65 of the various punches 33 as shown in Fig.
- 6 of the drawings, the disks are of different sizes, such as are required to make open-ended cylindrical crown cups 52, as shown in Fig. 21 of the drawings.
- When a sufficient supply of disks 37 has 70 been thus obtained, the disk-cutting mechanism is removed from its surface relation to the power mechanism and the machine is then adjusted for the next step, which is that resulting in the formation of the crown 75 cups 52.
- The first step in preparing the mechanism for the forming of the crown cups 52 after removing the disk-cutting mechanism, consists in removing the shoe plate 51. To this 80 end, cotter pins 53 are withdrawn from pins supporting the same. The wheel 49 is then rotated to lower the cross head 54. The lowering of the cross head 54 continues until the cup-shaping plate 55 rests firmly on the 85 bosses 47. The swing hooks 56 pivotally mounted on the cup-shaping plate 55 are then released from the pins 57 on the cross head 54 and moved to engage staples 58 in the base plate 48. The hooks 56 when so 90 disposed prevent any subsequent movement of the cup-shaping plate 55.
- The cross head 54 is slidably guided by the standards 46 and is provided with a series of plungers 59. The plungers 59, as 95 shown best in Fig. 3 of the drawings, vary in diameter, said plungers corresponding with open-ended sockets 60 in the cup-shaped plate 55. It will be noted that each plunger 59 is diminished in its diameter 100 relative to the sockets 60 with which each corresponds. The difference in the diameters between said plungers and their corresponding sockets, is the thickness of the metal from which the crown cups are to be 105 formed.
- As shown best in Figs. 10 and 11 of the drawings, the cup-shaping plate 55 is provided adjacent each of the sockets 60, with a recess 61. The recesses 61 are provided to 110 receive the disks 37, which are fed to the plate 55 when the cross head 54 is raised to the position as shown in Fig. 3. It will be observed by reference to Fig. 11, that the plungers are longer than the sockets 60. 115 The result of this construction is that when the cross head 54 is depressed to engage the plate 55, the plungers 59 extend beyond the lower ends of the sockets 60 and deliver the cups 52 formed thereby when the cross head 54 and the accompanying plungers are lifted.
- If it is desired to produce a crown of greater length than ordinary, this is accomplished by successively moving the completed crowns produced in a larger socket to a relatively smaller socket. The step-by-step action is advantageous in that the metal is not crowded to form the narrow 125 elongated cup to the extent that it would 130

be should the endeavor be made to form this cup by a single operation.

When a sufficient number of cups 52 have been produced, the machine is re-arranged 5 to finish the crowns 62 shown in Fig. 22 of the drawings. To form the denture 63 in the crowns, a series of male striking dies 64 are securely mounted in a die plate 65, as seen best in Figs. 14 and 15 of the drawings. 10 This die plate with its complement of dies 64, is attached by means of cotter pins 66 to the under side of the cup-shaping plate 55 when the same is raised to the position as shown best in Fig. 5 of the drawings. To 15 lift the plate 55 from the position shown in Fig. 3 to that shown in Fig. 5, the cross head 54 is lowered to engage the spacing plate 67, which is disposed on the plate 55. The hooks 56 are then released from the 20 staples 58 and are swung to engage the pins 57. The plate 67 is thick enough to prevent the extent of the plungers 59 beyond the lower opening of the sockets 60. When the 25 wheel 49 is now rotated, the cross head 54, plates 67 and 55 are lifted to permit the installation of the die plate 65. The die plate 65 is supported by cotter pins extended through the supporting pins 68 with which the plate 55 is provided as shown best 30 in Fig. 4 of the drawings.

As shown best in Fig. 19 of the drawings, the guide plate 65 is provided with a series of variously shaped sockets 69 for receiving the shanks 70 of the various striking dies 35 64. By this method care is taken to insure the correct placing of each striking male die 64 with reference to its corresponding female shaping die 71. The female shaping dies 71 are held in service in a die block 72 and rigidly clamped between side plates thereof.

As best shown in Figs. 12 to 17, inclusive, the block 72 is formed of two side plates. The plates are parted on the medial 45 line of the block, each plate having a half socket 73 formed therein. From each half socket extends an end-opening channel 74. The channel 74 when joined form in the die block, vent holes 75, to permit the escape of 50 gas medium used for casting or forming the female die 71 under pressure. This is usually accomplished by filling the sockets 73 with some suitable plastic material, and then forcing the corresponding striking die 55 64 on the plastic mass. Plaster of Paris is usually employed though other suitable materials may be used. When the pattern thus formed is set, the die block is opened to permit the withdrawal of the pattern. 60 From these patterns, metal dies are formed. They are placed in service position between the sides of the block 72, which is then closed by means of clamping bolts 76 and wing nuts 77 therefor. As shown best in 65 Fig. 12 of the drawings, the sides of the

block when in service encompass the standards 46 with sufficient force to hold the same firmly in service position. The die blocks 72 are furnished with positioning pins 78, with which holes formed in the 70 plate 65 register.

When the die block is placed in position, the cups 52 corresponding with the various sockets 73 are placed in the said sockets and the wheel 49 is manipulated to depress the 75 head 54, plate 65 and striking dies 64 mounted therein, the said dies 64 entering the cups 52 to force the same into the sockets 73. The descent of the cross head 54 is arrested when the dies 64 compress 80 firmly the end of the cup 52 to form the denture 63, and, if needed, to shape the side walls converting the cups 52 into the perfected crowns 62. The cross head 54 is then raised to furnish access to the dies 64, and 85 the crowns 62 carried thereby. The said crowns are then stripped from the dies 64 and the operation is repeated.

Provision is made so that the friction between the crowns 62 and the dies 64 shall 90 exceed the friction between the said crowns and the sockets 73. If necessary, the sockets 73 may be lubricated to insure said crowns being lifted from said sockets by the dies 64.

95

Claims.

1. A machine as characterized comprising a press having a base plate provided with standards, and a reciprocating head mounted 100 to slide on said standards; a die block for holding denture forming female dies; a plurality of operatively united denture forming male dies serially arranged; and means for predetermining the operating position of 105 said denture forming dies with reference to the dies in said die-block, said means embodying a supporting plate for said striking dies having a detachable connection with the head and provided with a series of variously shaped passages for holding the shanks 110 of said striking dies.

2. A machine as characterized comprising a hand press having a base plate; and a reciprocating head mounted in guided relation 115 to said base plate; a die block for holding a series of female shaping dies, said block being parted on the longitudinal vertical plane for separating said block on the medial plane; and means for holding said die block 120 in operative relation to said reciprocating head, said means embodying guide standards for said head, and means on said block for clamping said standards.

3. In a machine of the character described, 125 a base provided with standards, a cross head slidable on the standards, provided with plungers, a cup shaping plate mounted to slide on the standards and having open-ended sockets, and means for detachably se- 130

curing the said plate to either the base or cross head, whereby the plate when secured to the cross head serves to carry a member of a crown forming means.

5. 4. In a machine of the character described, a base, standards projecting from the base, a cross head slideable on the standards and provided with plungers, means for operating the cross head, a cup-shaping plate slideable 10 on the standards and having open ended sockets, and hooks carried by the said plate and adapted to be engaged with the base or the cross head.

5. In a machine of the character described, 15 a base, standards projecting from the base, a cross head slideable on the standards and provided with plungers, means for operating the cross head, an apertured plate detachably secured to the cross head, an apertured 20 spacing member between the said plate and cross head, a die plate carrying dies and de-

tachably secured to the apertured plate, and a die block carrying female dies and mounted on the standards of the base.

6. In a machine of the character described, 25 a base provided with standards, a cross head slidably mounted on the standards, means for operating the cross head, a plate detachably secured to the cross head, a die plate detachably secured to said plate, and a die 30 block carrying the female dies and detachably mounted on the standards of the base.

7. In a machine of the character described, a base provided with standards, a cross head slidably mounted on the standards, means 35 for operating the cross head, a male die plate carried by the cross head and provided with dies, a sectional female die block and means for securing the sections of the die block together and the block on the standards of the 40 base.

IGNACIO NAVARRO M.
